UNITED STATES PATENT OFFICE

162,208

SQUEEZE PLATE FOR MOP

Walter F. Miller, Dayton, Ohio

Application May 26, 1950, Serial No. 10,220

Term of patent 14 years

(Cl. D9—2)

To all whom it may concern:

Be it known that I, Walter F. Miller, a citizen of the United States, residing at Dayton, State of Ohio, have invented a new, original, and ornamental Design for Squeeze Plate for Mop, of which the following is a specification, reference being had to the accompanying drawing, forming a part hereof.

Figure 1 is a plan view of a squeeze plate for mop, showing my new design;

Figure 2 is a front elevational view thereof;

Figure 3 is a plan view of the bottom side thereof; and

Figure 4 is an end view thereof.

I claim:
The ornamental design for a squeeze plate for mop, as shown.

WALTER F. MILLER.
